COIN-FREED LOCKING DEVICE FOR TYPEWRITERS

Karl Dietrich, Hanover, Germany

Application May 20, 1932, Serial No. 612,554.
Renewed January 7, 1935. In Germany May 23,
1931

1 Claim. (Cl. 197—198)

This invention has for its object to allow typewriters to be used for a certain time against payment, for example in writing rooms of hotels, homes and the like.

5 Several devices are known which serve the same purpose, but which do not take in consideration the chief factor, namely the collection of money, because the releasing device of the typewriting mechanism, for example according to German Patent 304,861 and U. S. A. Patents 923,142 and 10 923,143, is arranged only for a certain number of letters or lines without taking into consideration the capability or any intentions of the typist. In the case of a different arrangement, wherein the typewriting mechanism is released for a certain 15 time, as in the present invention, the device as shown in German Patent 246,979 consists, similar to the above mentioned devices operating according to the number of letters or lines written, 20 of a complicated mechanism which is brought into connection with certain parts of the typewriter. In both instances the devices require a more or less great constructional alteration of the typewriter according to the type of machine. Contrary to these known arrangements that according to the invention has no direct connection with the machine and operates absolutely freely and independently, and also absolutely reliably because there are no connections, as those in the 25 known devices by elastic arrangements of different types.

Several embodiments of the invention are illustrated diagrammatically in the accompanying drawing in which:—

35 Fig. 1 shows in elevation the device cooperating with the key bars, the locking bar being in its extreme lower position and controlled by a wedge.

Fig. 2 shows the device with the locking bar in raised or locking position.

40 Fig. 3 is a top plan view of Figs. 1 and 2.

Fig. 4 shows a modified form of construction with locking bar controlled by a cam.

Fig. 5 shows a third form of construction with locking bar controlled by an eccentric.

45 Fig. 6 shows a fourth form of construction with locking bar controlled by a lever mechanism.

The device consists of a locking rod or bar *a*, which extends from below to within a short distance of the key bar *b* (Figs. 1 and 2), or if the construction of the typewriter is such as to make it seem more practical, to near the margin stop, the releasing bar of the shifting mechanism or directly to the shifting mechanism of the machine. The locking bar *a*, as shown in the drawing, may be constructed in various manners according to the shape or construction of the key bars, of the releasing bar or the like. The locking bar *a* has a pin *c* which is inserted in a tube *d* in such a

manner that it is shifted through the intermediary of an adjusting ring *g* by the tube *d* which can move freely up and down in a stationary guide tube *e*. The length of the pin *c* depends upon the construction of the machine. The guide tube *e*, 5 the tube *d* and the pin *c* may be of any desired cross-section. On the lower end of the tube *d* a roller *f* (Figs. 1 to 4) or a ball *g'* (Figs. 5 and 6) is arranged in such a manner that through the intermediary thereof and with the aid of a wedge- 10 shaped surface *h* of a shiftable plate *i* (Figs. 1 to 3) or with the aid of a cam *j* (Fig. 4) or of an eccentric *k* (Fig. 5) or of a lever transmission *l* (Fig. 6) the tube *d* is raised and lowered. The plate *i* is rigidly connected with a shiftable rod *m* (Figs. 1 15 to 3) so that during the reciprocation thereof the locking bar *a* is shifted towards or away from the key bar *b*, the releasing bar or the like.

Fig. 1 shows the locking bar *a* in inoperative or lowered position, in which the typewriter is 20 free for use, whereas in Figs. 2, 4, 5 and 6 the locking bar *a* is in operative or raised position locking the machine as the key bar cannot be depressed. The device above described is connected to a clock work and to a coin operated mechanism which is 25 arranged in such a manner that the rod *m* can be shifted in the direction of the arrow (Fig. 2) and the typewriting mechanism liberated for use only after the insertion of a coin. By shifting the rod *m* a clockwork mechanism is simultaneously wound 30 and set in operation, and a locking device prevents the returning of the rod *m* and of the plate *i*. After a certain adjustable time has elapsed, the clockwork disengages the locking mechanism and a spring *o* (Fig. 3) pulls the rod *m* back into its 35 initial position (Fig. 2). Thus, the tube *d* is again lifted, the locking bar *a* bears against the key bars *b*, the releasing bars and the like and prevents the typewriter from being used.

The device is preferably arranged in a box un- 40 der the table on which the typewriter is fixed, this box being adapted to be locked.

I claim:—

A coin-freed device for locking typewriters and for releasing same for use for a predetermined 45 period of time, comprising in combination with movable elements of the typewriter, a guide element, a tubular transmission element shiftable in said guide element, a locking element exchangeably carried in one end of said tube, a rolling ele- 50 ment on the other end of said tube, and a cam contacting with said rolling element and adapted to cooperate with said tubular transmission ele- 55 ment to shift said locking element into and out of the range of movement of said typewriter ele- 55 ments.

KARL DIETRICH.
